UNITED STATES PATENT OFFICE

2,488,059

IMPALING PIN TARGET

George Greenberg, Brooklyn, N. Y.

Application April 28, 1948, Serial No. 23,831

9 Claims. (Cl. 273—104)

1

This invention relates to target games, and has for its main object to provide a game of this character in which the missiles may be made to temporarily adhere to the target and then to be easily removed therefrom for a new play.

Most of the devices now used having these characteristics, shoot pointed missiles, like arrows and darts, which penetrate the target board. Obviously, these missiles are very dangerous, particularly in the hands of children, and one object of my invention is to provide a target game of this type, in which the missiles are entirely harmless, and a target board is provided with spikes or the like, on which the missiles may be impaled in a temporary manner, and then easily removed therefrom.

A further object of this invention is to provide means which, in a way, may be called semi-automatic, whereby upon the termination of the shooting, all the missiles which may have been impaled on such spikes may be at once removed with one simple movement, in a safe manner.

Still further objects of this invention will be apparent as the specification of the same proceeds, or will be pointed out therein, and, among others, I may mention: to provide a target game as indicated hereinbefore, in which the spikes will be secured in a comparatively stationary member and a second removable member will be applied in front of said stationary member, the spikes protruding through said movable member, whereby upon moving this member, the missiles may at once be pulled off the spikes, and in which game the spikes will protrude to a comparatively small distance to the front of the removable member, thereby making the game still more safe and the removal of the missiles easier, and in which game the parts will be simple, inexpensive to manufacture, easy to set up either on a vertical support like a wall or pole, or on a special support, and wherein the parts may be disassembled in an easy and quick manner, and the device stored or shipped in this manner, being adapted to be quickly and easily set up when desired.

In the drawings forming a part of this specification and accompanying the same:

Fig. 1 is a semi-diagrammatic front view of one form of my invention, adapted to be secured on a vertical support, like a wall, post or the like;

Fig. 2 is a side view thereof, the operation of the device for the removal of the missiles being indicated in dotted lines;

Fig. 3 shows a preferred form of a missile;

Figs. 4 and 5 show a modification of my device

which may be set up in an easily demountable manner on a support on the ground.

Referring now to the drawings, more in detail by characters of reference, the numeral 10 indicates said first form of a target game device in general, the same being composed of rear and front plate members 11 and 12. The rear member may have upper and lower perforated ears or projections 13 and 14 by which it may be secured 5 on a wall or the like, as through the use of appropriate nails, bolts, etc. A plurality of nails or spikes 15 are secured into the stationary rear plate 11, the same being preferably arranged in concentric circles, as indicated, whereby target circles at predetermined distances from the center of the device will be provided, each circle having a value mark thereon as shown by the numerals 16, 17, 18, etc. A spike 19 may be provided in the center of the device, being the so-called "bull's 10 eye" and giving the highest value when hit.

The front plate 12 will have comparatively wide apertures 20 through which the spikes 15 project, a short forward end 15a thereof being in the front of the plate 12 and arranged in said circles 16, 17, 20 18, etc.

The plate 12 may be hinged on the rear stationary plate 11 as indicated at 21, and normally any appropriate spring clips 22 may keep the same in its operative position shown in the drawing.

30 Any appropriate missile of a material which may be penetrated by the spike ends 15a may be used and shot at the target by any appropriate device well known in this art, like an air rifle. As it is well known, some of these rifles are adapted 35 to shoot cork missiles, practically in the shape of a stopper, and at 23 I indicate such a missile as the preferred form thereof to be used in my device. Such a missile will be harmless when flying through the air even if by chance it may hit a person. It will be adapted to be easily impaled on the spikes 15 and comparatively easily removed by pulling the same off of it, and, at the same time, by its inherent resiliency it will close the hole so produced and will be ready for a new 40 use.

45 A handle or grip 24 may be provided, extending from the top of the hinged plate 12, and when the shooting is terminated and the score established, plate 12 may be rocked forwardly on its hinges 21, 50 as indicated by the dotted lines in Fig. 2, said grip 24 being adapted to be conveniently used for this purpose, and by such a movement, obviously, all the impaled missiles 23 will at once be removed from their respective spikes.

An appropriate container may be placed under-

neath the target whereby the unsuccessful missiles will drop thereinto, and when the play is terminated, all the impaled missiles may also be caused to drop into said container.

The front plate 12 now may be turned back into its operative position, the spring clips 22 snapped over the top of the stationary plate 11, and the device will be ready for a new play.

In Figs. 4 and 5 I show a modification of my device. In this modification the device will have its own support whereby it may be set up on the floor of a room or on the ground in the open air.

In this modification the numeral 25a indicates the relatively stationary rear plate member having a somewhat different construction from the one described hereinbefore, as will be explained presently.

Spikes 15 are, again, arranged in said rear plate 25a, but the front plate 12 in this modification is replaced by a screen member 26 which may be made of wires or any other appropriate form, and, again, may be hinged to the front plate, as at 27.

It also may have any appropriate spring clips 28 to keep the same on the front of the stationary plate 25a, when the game is played, but to permit an easy moving thereof on its hinges 27 for the removal of the missiles at the end of the game. The screen front plate 26 may, again, have a handle 29 and the play and operation of the device will be entirely similar to that described in connection with the first embodiment thereof.

A supporting structure, generally indicated by the numeral 30, however, is provided whereby the device may be set up on the ground. The supporting structure may have two leg members 31 with appropriate wide bases 32. A slot 33 is cut downwardly in the top of each leg 31, and when setting up the device the legs with their slots are placed at a desired distance and in registering relation. A plate like cross member 34 is now dropped into the slots 33 having a somewhat wider central portion 35, so that its movement in a horizontal direction will be prevented, and the whole frame structure 30 will be made more rigid.

The lower portion of the stationary rear plate 25a will be made wider, as at 36, and will have a downwardly open slot 37 provided therein, whereby it may be slipped over the wide center portion 35 of the cross member 34.

Bolts 38 or any other appropriate easily removable device may be employed to further secure the target carrying plate on the cross member 34.

It will be seen that the second embodiment of my device provides a target of the character in view, which may be easily disassembled and stored or shipped in parts, while the parts are adapted for an easy and quick assembling when the device is to be used.

A second grip or handle 24a may also be employed in the first embodiment of my device for the relatively stationary rear plate thereof, and a similar second handle 29a in the second embodiment of my device to aid in removing the missiles when the game is finished. It will be obvious that the player may grip the handle 24 or 29 and swing the front plate against the rear one as described, but at the same time, with his other hand, he may grip the second stationary handle 24a or 29a thereby counteracting the forward tendency of the whole device and preventing an undue strain on, or maybe an upsetting of, the stationary part thereof.

While I have shown preferred embodiments of my invention, it is to be understood that changes and variations may be resorted to in the elements, construction and combinations of my invention, and I reserve my rights to such changes and variations as are within the spirit of this specification, and the scope of the claims hereunto appended.

What I claim as new and desire to protect by Letters Patent of the United States, is:

1. In a target game, the combination of a stationary member, a plurality of spikes projecting from said member and arranged in a predetermined design to indicate various target values, a movable member in front of said stationary member, said movable member having apertures through which said spikes may project, and indicia on the front of said movable member to indicate the target value of the various spikes, said spikes being adapted to receive missiles shot at said target and to be impaled on said spikes said missiles being easily removable therefrom, means to temporarily secure said front member on said rear member said front member being adapted to be moved away from said stationary rear member when desired, whereby upon such a movement thereof all the missiles impaled on said spikes may be at once removed.

2. In a target game, a stationary plate, spikes projecting from said plate arranged in a predetermined design to indicate various target values, a plate in front of said stationary plate being hinged thereto and adapted to be moved away therefrom by a rocking motion on its hinges, said front plate having apertures therein through which said spikes may project, and target marks on said front plate indicating the values of the various spikes projecting to the front thereof, said spikes being adapted to receive missiles shot at the target and to be impaled on said spikes said missiles being easily removable therefrom, whereby after the shooting at the target is finished all the missiles impaled on the various spikes may be removed by turning said front plate on its hinges away from said rear plate.

3. In a device, as set forth in claim 2, yielding means to removably secure said two plates to one another.

4. In a device, as set forth in claim 2, spring clips on the top of said front plate adapted to engage the top of said rear plate when the plates are closed upon one another and thereby secure them to one another in a yielding, removable, and repeatable manner.

5. In a device, as set forth in claim 2, said hinged apertured front plate being in the form of a screen.

6. In a device, as set forth in claim 2, a support for said rear plate comprising two legs, a cross member placed over said legs, said rear plate being secured on said cross member.

7. In a device, as set forth in claim 6, said legs, said cross member, and said rear plate being removably secured to one another whereby the device may be assembled or disassembled in an easy and quick manner.

8. In a device, as set forth in claim 2, a support for said rear plate comprising two legs having registering upwardly open slots, a plate shaped cross member the end of the same being placed into said slots, the bottom of said rear stationary plate having a slot therein whereby it is adapted to be placed over the center portion of said cross member, and removable means to secure said rear plate on said cross member.

9. In a device, as set forth in claim 2, a handle member secured on the front movable plate and another handle member on the stationary plate whereby when said front member is swung for removing the missiles, said stationary member may be better kept in its place.

5
GEORGE GREENBERG.
